DIE FOR LAYING WIRE ROPE AND WIRE ROPE STRANDS

Original Filed Sept. 7, 1928 2 Sheets-Sheet 2

UNITED STATES PATENT OFFICE

JOSEPH E. EVANS, OF BEDFORD, INDIANA, ASSIGNOR OF ONE-FOURTH TO CHARLES S. KNIGHT, OF CHICAGO, ILLINOIS

DIE FOR LAYING WIRE ROPE AND WIRE-ROPE STRANDS

Application filed September 7, 1928, Serial No. 304,455. Renewed September 26, 1929.

My invention relates to a device designed to form a portion of a machine for manufacturing a wire cable or a group of wire forming a strand of such a cable, from a plurality of spirally coiled wire strands, and particularly relates to a die or forming and sizing device which is located adjacent the rotating head which forms the turns of the wire entering into the rope, strands of the rope, and which acts to lay and compress the strands uniformly to form the finished rope, or strand. The object of my invention is to provide a wire-laying multiple-element die which shall exert a strongly compressive action on the group of wires passing through the device and being formed into a finished rope or cable element for a considerably greater extent of the path travel of the cable than usual in the case of dies ordinarily employed in wire-rope making machines, while avoiding undue frictional drag of the rope against the die members, and to make provisions in such a multiple-element die for adjusting the compressive effect of the die elements, as well as for interchanging the die members to enable the machine to be used for manufacturing wire ropes or rope strands of various sizes. Other and incidental objects and advantages of my invention will be apparent from the description hereinafter given, the essential elements of my invention being more particularly pointed out in the appended claims.

In the drawings,

Figure 1 is a simplified semi-diagrammatic view on a small scale, illustrating in side view the relation of my novel die to the other elements of a cable-making machine;

Fig. 2 is a central longitudinal section of the device;

Fig. 3 is a side view of one of the four adjustable backing plate members providing tracks for the endless chains of connected die elements detached;

Fig. 4 is a cross-section of the device;

Fig. 5 is a front end view of the same;

Figs. 6 and 7 are views of opposite sides of one of the four frame bars, detached;

Fig. 8 is a plan view of one of the die elements of the device detached;

Figs. 9 and 10 are detail views of one of the die elements with an associated roller, shown in side and end elevation, respectively; and

Fig. 11 is a top plan view of the complete device, on a relatively small scale.

Like reference characters indicate like parts in all the figures of the drawings.

The particular construction of the parts of a wire-rope-making machine in which my novel rope-laying die is employed, other than the die itself, immaterial, excepting that the machine includes some form of rotating head (indicated diagrammatically at A in Fig. 1), carrying reels of wire from which the several strands of wire B which enter into the completed rope are conducted as they are laid down in a spiral path as they enter the die, and that the machine ordinarily includes also a power driven drum or reel (marked C on Fig. 1), which serves to draw the wire strands and completed cable B through the device, and coil the cable up for storage and shipment. Wire-rope-making machines of the general construction mentioned are well-known in the rope-making art, and my improvement relates to the die-member of such machines only.

The die frame, which it will be understood is ordinarily secured in fixed position in the frame of the machine in appropriate relation to the other parts above mentioned, in the present instance consists of end plates 1 and 2, secured to four similarly-formed frame bars 3, 4, 5 and 6 by means of bolts 7 and dowel pins 8. The end plate 1 is provided with a closing-in bushing 9 having a flared internal opening somewhat larger than the finished rope. This bushing may either be secured in fixed position in the end plate by means of a set screw 10, as shown, or may be free to rotate in the end plate.

The frame bars are machined to provide guide-ways adapted to receive four endless chains of connected die elements 11, which are connected by link members 12 engaging pintles 14 which pass through such link members and die elements. These pintles also form pivots for grooved rollers 13, arranged severally between pairs of bearing lugs 11.

extending inwardly or rearwardly from each die element. The opposite sides of the body of each die element are cut away, as indicated at X, on planes approximately radial of the axis of the passageway for the cable between the four chains of connected die elements, and the segmentally cylindrical working face Y of each die element extends through an arc of slightly less than a quadrant of the cylinder. Preferably, and as shown, one end of each die element, as the leading end, is beveled on its opposite side edge, as indicated at Z, and the opposite end is formed with corresponding flanges, marked Z'; so that the die elements will tend to nest together in alignment during their travel, and sidewise movement will be prevented.

The grooved rollers of the four connected chains are arranged to ride upon track rails 15 formed upon the peripheral faces of four round-ended tensioned backing members 16, one associated with each chain. The ends of the track rails are rounded and of such contour as to permit the forward and following 25 ends of the working face of the die elements to enter into and depart from working engagement without pinching the group of strands, and the die elements may be slightly cut away in furtherance of the same purpose. 30 Each backing member is mounted to permit movement radially of the rope passage between guide faces formed on the frame bars on each side of it, but is restrained from longitudinal movement by block portions 17 extending laterally from the side faces of the track member and working in recesses 18 formed in the frame bars.

The several backing members, and consequently the die elements associated with them are secured in place in the die frame and 40 yieldingly stressed towards the rope passageway between the die elements through a pair of retaining shoes 19-19 arranged to straddle the space occupied by the backing members and chain of die elements between adjacent frame bars on each side of the frame. The frame bars (see Figs. 4, 6 and 7) are formed with flange portions *a* on each side of a central space, and the shoes 19, which are slightly 45 shorter than the opening between the flanges *a*, are formed with opposite recurved flange portions *b* arranged to hook under the flanges *a*. Each retaining shoe 19 is formed with a threaded seat to receive a set screw 20 which 50 bears against a saddle 21^a upon an elliptical spring 21 bearing at its ends against one of the block portions 17 of the particular backing member 16, the tension of the four springs 21 acting upon a particular backing member 55 thus stressing the associated chain of die elements cooperating with its track rail 15 radially of the rope passageway, and the combined tension of all of the springs serving to create radial inward pressure extending practically entirely around a cable pass-

ing between the die elements through the device. Obviously, the tension of the springs may be so adjusted that the backing members, when used in connection with wire strands and die elements of given dimensions, will bring up against the inner faces of the recesses 18, as shown in Fig. 4, the working faces of the die elements thus defining a standard minimum rope passageway, and the die elements being free to yield radially outward to accommodate a variation in size of the wire strands and formed cable passing through the device. By adjustment of the set screws, the tension of the springs may be regulated as required for the best results. Other forms of tensioning springs than the elliptical spring particularly described may of course be employed.

It will be understood that I contemplate the use of interchangeable chains of connected die elements to enable the device to be used to form cables of different diameters, and this may readily be accomplished by loosening the set screws 20 and sliding the retaining shoes 19 one at a time opposite the gap between the flanges *a-a* of the frame bars to permit their removal.

The operation of the die will readily be understood from the foregoing explanation of its construction. The finished cable or cable strand, and the wires entering into it are drawn through the device under a proper degree of tension, by means of the winding drum C before mentioned, or otherwise, from the rotating head A which delivers to the device the separate wires entering into the cable. On its way through the device, the wire strands first pass through the closing-in bushing 9 which directs the strands, spirally coiled but not compacted and sized to final form, into the passageway between the chains of die elements. The frictional drag of the strands upon the die elements of the four endless chains carries the die elements along with the strands, the latter being subjected on their way to the compressive action of the die elements exerted through the springs 21, while the anti-friction rollers riding on the track rails 15 of the backing members 16 permit the die elements and associated chain members to travel freely with the cable as it is being formed, and return around such backing members. In this manner, the wire strands of the cable are compacted and compressed so that they are deadened or given a permanent set in the strand, or finished cable, and will retain their position therein without tendency to unwind. Upon emerging from the device the rope passes to the winding drum and is stored upon it.

It is obvious that while the machine as illustrated in the drawings and above described consists of four similar sections and chains of multiple die members, the number of chains and sections could be either greater

or less,—three, or five, for instance,—the chains of course traveling in angularly equidistant planes extending radially of the center of the rope passage and the working and meeting faces of the die members and other parts being modified accordingly.

It is further obvious that other anti-friction means for supporting the die members than the rollers above described may be employed, though I regard the particular construction described as efficient and desirable.

I claim:

1. In a wire rope making machine, a compression device for laying the strands of the rope including a frame and a plurality of endless chains of connected die elements mounted to travel with their inner flights extending parallel with each other adjacent the center of the device, said die elements being formed with cylindrically segmental working faces arranged to engage the rope and together form a rope passageway.

2. In a wire rope making machine, a compression device for laying the strands of the rope including a frame and a plurality of endless chains of connected die elements mounted to travel with their inner flights extending parallel with each other adjacent the center of the device, said die elements being formed with cylindrically segmental working faces arranged to engage the rope and together form a rope passageway, and anti-friction backing means for holding said die elements against a rope within said passageway.

3. In a wire rope making machine, a compression device for laying the strands of the rope including a frame and a plurality of endless chains of connected die elements mounted to travel with their inner flights extending parallel with each other adjacent the center of the device, said die elements being formed with cylindrically segmental working faces arranged to engage the rope and together form a rope passageway, and being equipped with anti-friction rollers, and track members carried by said frame and engaged by said rollers for holding said die elements against a rope within said passageway.

4. In a wire rope making machine, a compression device for laying the strands of the rope including a frame and a plurality of endless chains of connected die elements mounted to travel with their inner flights extending parallel with each other adjacent the center of the device, said die elements being formed with cylindrically segmental working faces arranged to engage the rope and together form a rope passageway and being equipped with anti-friction rollers, and backing members mounted in said frame and formed with tracks engaged by said rollers for holding said die elements against a rope within said passageway, said backing plates

being adjustable in said frame radially of said passageway.

5. In a wire rope making machine, a compression device for laying the strands of the rope including a frame and a plurality of endless chains of connected die elements mounted to travel with their inner flights extending parallel with each other adjacent the center of the device, said die elements being formed with cylindrically segmental working faces arranged to engage the rope and together form a rope passageway and being equipped with anti-friction rollers, and backing members severally formed with tracks engaged by said rollers for holding said die elements against a rope within said passageway, said backing members being mounted to permit their movement radially of said passageway, and spring tension means for stressing said backing members toward the rope.

6. A device according to claim 1 in which said frame includes end plates and a plurality of frame bars spaced apart and arranged to provide guideways for the chains of connected die elements.

7. In a wire rope making machine, a compression device for laying the strands of the rope including rigidly connected frame bars arranged to form a plurality of guideways extending radially from the center line of the device, an endless chain of connected die elements arranged to travel in each guideway, said chains including anti-friction contact members, backing members severally arranged inside the loops of the chains and each formed with a track face extending around its outer face arranged to support said contact members, and means for connecting said frame and said backing members.

8. In a wire rope making machine, a compression device for laying the strands of the rope including rigidly connected frame bars arranged to form a plurality of guideways extending radially from the center line of the device, an endless chain of connected die elements arranged to travel in each guideway, said chains including anti-friction rollers, backing members severally arranged inside the loops of the chains and each formed with a track for said rollers extending around its outer face, and means for connecting said frame and said backing member.

9. In a wire rope making machine, a compression device for laying the strands of the rope including rigidly connected frame bars arranged to form a plurality of guideways extending radially from the center line of the device, an endless chain of connected die elements arranged to travel in each guideway, said chains including anti-friction rollers, backing members severally arranged inside the loops of the chains and each formed with a track for said rollers extending around its outer face, and spring tension means on said

frame for stressing said backing members radially inward.

10. A compression device according to claim 7 which includes spring tension means and retaining shoes on the machine frame equipped with adjusting screws arranged to vary the stress of said spring tension means.

11. A compression device according to claim 7 in which said backing member is an elongated flat plate having rounded ends and provided with block portions on its sides, and said frame bars are provided with radially-extending recesses arranged to receive said block portions of the backing member.

15. 12. A compression device according to claim 7 in which said backing member is an elongated flat plate having rounded ends and provided with block portions on its sides, and said frame bars are provided with radially-extending recesses arranged to receive said block portions of the backing member, and in which springs housed in said frame bar recesses and bearing on said block portions of the backing member are arranged to stress 25 such backing member inwardly.

13. In a wire rope making machine, a compression device for laying the strands of the rope including a frame formed with a lead-in opening and a plurality of endless chains of 30 connected die elements mounted to travel with their inner flights extending parallel with each other adjacent the center of the device, said die elements being formed with cylindrically segmental working faces arranged to engage the rope and together forming a rope passageway aligned with said lead-in opening.

14. In a wire rope making machine, a compression device for laying the strands of the 40 rope including a frame, and die elements arranged in a plurality of trains of contiguous elements arranged to travel in closed paths in planes extending radially of the center of the device with the working inner faces of 45 the dies extending in parallel lines adjacent the center of the device, said die elements being formed with cylindrically segmental working faces arranged to engage the rope and together form a rope passageway.

50. In testimony whereof, I have subscribed my name.

JOSEPH E. EVANS.
